JULIUS KAHN, OF DETROIT, MICHIGAN, ASSIGNOR TO TRUSSLED CONCRETE STEEL COMPANY, OF DETROIT, MICHIGAN, A CORPORATION OF MICHIGAN.

CONCRETE FLOOR CONSTRUCTION.

1,074,953.

Specification of Letters Patent.

Patented Oct. 7, 1913.

Application filed January 5, 1912. Serial No. 369,627.

To all whom it may concern:

Be it known that I, JULIUS KAHN, a citizen of the United States, and a resident of Detroit, in the county of Wayne and State 5 of Michigan, have invented a new and useful Concrete Floor Construction, of which the following is a specification.

This invention relates to the construction of light, reinforced concrete floors, and its 10 object is to provide means for rapidly and economically forming such floors with air-spaces in the interior of the concrete, which floor can be rapidly constructed at low cost.

In the accompanying drawing Figure 1 15 is a perspective view of this improved floor construction. Fig. 2 is a perspective view of one of the forms or molds for forming the hollow air-spaces. Figs. 3 and 4 are views on a larger scale showing the method 20 of forming the corners of the forms or molds.

In fire-proof building construction, where stability combined with light weight is desired, it is common to employ a ceiling slab 25 of concrete, integral with parallel joists extending downwardly from the slab, which joists are reinforced by means of steel tension members. Such floors are often objectionable because the joists are always in full 30 view. Where flat ceilings are desired, it is customary to place terra-cotta tiles in parallel rows upon a false-work, then to place the reinforcing members in the spaces between the rows, and finally to pour concrete into 35 the spaces between the rows and over the entire area, thus forming a slab of concrete strengthened by reinforced joists which are separated by the terra-cotta tiles. These terra-cotta tiles are heavy and add little to 40 the strength of the floor; on the contrary, their weight requires the reinforced concrete portion of the floor to be made heavier in order to support the additional dead weight.

In the construction shown in the drawings 45 the terra-cotta tiles are replaced by forms or molds of pressed sheet-metal having tops 1 and sides 2. These forms or molds are pressed up from thin sheet-steel, and formed 50 with transversely corrugated tops and sides. To prevent concrete entering the ends of these molds, pressed sheet-metal caps may

be placed over their ends, which caps have ends 3, sides 4 and tops 5. These ends also are corrugated as shown in Fig. 2. The 55 lower edges of the sides 2 and 4 are preferably serrated so that the sharp points 6 may be utilized to prevent the lower edges from moving laterally. In the construction of a floor of this character, sheets of metal-lath 7, preferably provided with ribs 9, are laid directly on the false-work to extend over the entire area to be spanned. The sheet-metal forms or molds are then positioned in parallel rows, the points 6 engaging the meshes of the lath. If ribbed-lath is employed, as shown in the drawing, the ribs will extend up between the points 6. Should a point come immediately above a rib, then the rib may be bent laterally with 70 little effort.

The reinforcing steel bars 10, of any desired type, are then placed in the spaces between adjacent molds and the concrete 11 filled in between and over the molds. This 75 concrete will usually form a bond with the metal-lath at the bottoms of the joists, but to insure more perfect union, small holes may be punched through the ribs 9 and wires 12 pushed through these holes and 80 bent upward, as shown in Fig. 1. As a result, when the concrete sets around these wires, the sheet-metal will be firmly tied in position. The lower face of the lath may then be plastered in the usual manner.

To form the molds in such a manner as to give them maximum strength where they would otherwise be weakest, the construction shown in Figs. 3 and 4 is employed. The sheet-metal is forced outward from the 90 concave parts 13 of the corrugations so as to form ribs 15, extending outward to nearly the line of the convex parts 14. These ribs not only serve to stiffen the entire structure, but they also serve to prevent the forms or 95 molds from slipping out when the floor is complete, as they enter the concrete and key the forms or molds in place. If desired, the lower face of the metal-lath may be covered with a thickness of plaster 16.

Owing to the light weight of these molds, they can be shipped long distances at low rates, and as the sides slightly diverge downwardly, the forms or molds can be "nested"

and are thus protected from injury. Owing to their lightness and comparatively large size, the work of placing them in position is only a small fraction of that required to 5 position terra-cotta tiles for the same area.

I claim—

1. In a concrete floor construction, the combination of reticulated metal-lath, a series of sheet-metal forms lying parallel to 10 each other on the lath and having serrated lower edges which serrations engage in and interlock with the meshes of the lath, reinforcing bars in the spaces between the forms, and concrete extending over the molds to 15 form a slab and between the forms to form joists.

2. In a concrete floor construction, the combination of reticulated ribbed-metal-lath, a series of sheet-metal forms comprising 20 transversely corrugated sides and tops and having serrated lower edges engaging and interlocking with the meshes of the lath, said forms lying parallel to each other on the lath transversely to the ribs of the lath, concrete extending over the tops of the forms 25 and into the spaces between them, reinforcing bars in the concrete between the forms, and supporting wires extending through the ribs of the lath and up into the concrete.

3. In a concrete floor construction, the combination of reticulated metal-lath extending over the area to be spanned, a series 30 of sheet-metal molds formed with transversely corrugated sides and tops lying parallel to each other on the lath and having their lower edges formed with teeth to engage in and interlock with the meshes of the lath, caps extending over the ends of the forms and formed with transversely corrugated tops, ends and sides, concrete extending over and between said forms, and 35

reinforcing bars in the concrete between said forms.

4. Sheet-metal floor molds consisting of transversely corrugated sides and tops, the 45 metal at the lines of juncture of the sides and tops being forced outward from the bottoms of the concave parts to form lines of stiffening ribs.

5. Sheet-metal floor molds consisting of 50 transversely corrugated sides and tops reinforced by integral lines of stiffening ribs at the lines of juncture of the sides and tops.

6. In a concrete floor construction, the combination of ribbed sheet-metal, a series 55 of sheet-metal forms extending across the ribbed sheet-metal and having their lower edges notched to receive the rib of the ribbed sheet-metal, concrete extending over and between the forms, and reinforcing members 60 between the forms.

7. A sheet metal form for concrete floor construction, of open box-like shape comprising top and side walls, the lower edges of said side walls being provided with projections 35 adapted for engagement with the meshes of lathing, thereby preventing displacement of the form when positioned in the floor.

8. A sheet metal form for floor construction of open box-like shape comprising a top and sides corrugated at their lower edges, and braces integral with the top and sides connecting them. 70

In testimony whereof I have signed this 75 specification in the presence of two subscribing witnesses.

JULIUS KAHN.
